UNITED STATES PATENT OFFICE.

FRANK J. MUHLFELD, OF NEW YORK, N. Y.

FLATTENING CONICAL HAT-BODIES.

1,052,504.

Specification of Letters Patent. Patented Feb. 11, 1913.

Application filed May 10, 1911. Serial No. 626,337.

To all whom it may concern:

Be it known that I, FRANK J. MUHLFELD, a citizen of the United States, residing at 805 Crotona Park North, New York, county 5 of New York, and State of New York, have invented certain new and useful Improvements in Flattening Conical Hat-Bodies, fully described and represented in the following specification and the accompanying 10 drawings, forming a part of the same.

This invention relates to a process of stretching conical hat-bodies in any desired degree, and the invention is especially useful for changing such bodies to a flat form.

15 The invention is applicable to hat-bodies either before or after the felting operation has been completed, and avoids the necessity of so manipulating the hat-bodies as to gradually flatten the same while passing 20 through the forming, hardening or felting processes.

The invention also permits the hat-body to be originally felted in the form of a steeper cone than is practical where any other process 25 is employed to flatten a cone-shaped body into a disk.

The process consists of a series of steps which will hereinafter be more fully described, and will be claimed in the appended 30 claims.

The invention will be understood by reference to the annexed drawing, which illustrates one specific means of carrying out the invention; but the means used to practise 35 the invention is wholly immaterial.

In the drawing, Figure 1 is a perspective view of a conical body; Fig. 2 is a plan of a flat body which may be made from such conical body; Fig. 3 is a perspective view of 40 the body folded once; and Fig. 4 is a perspective view of the body folded twice. Fig. 5 is a diagram illustrating the application of the stretchers to the folds of such doubly folded bodies; and Fig. 6 shows the doubly 45 folded body thus stretched to quadrantal form, which adapts it to form a flat body when unfolded.

Fig. 1 is a perspective view showing a hat-body *a* of the ordinary conical form, the 50 opening *b* at the base of which is small in relation to the height of the body. Fig. 3 shows the same body flattened, forming primary folds *c* and *c'* at its opposite edges, and the sides of the fabric between the folds 55 parallel with one another. Fig. 4 shows the body of Fig. 3 thus folded again with the

primary folds *c* and *c'* one upon the other, and making two secondary folds *d*, *d'* at the opposite edge of the body one within the other, and the four thicknesses of fabric 60 parallel with one another when thus folded. The folds all extend through the apex *a'* of the body.

As the purpose of the invention is to convert a conical hat-body into a flat disk, and 65 the process is essentially a flattening one, I have used the terms "flattening" and "flattened" herein exclusively in connection with the operation of the process, and it is therefore undesirable to use the same terms in 70 connection with the first folding of the body, although such first folding does involve a flattening or collapsing of the cone to form flat sides. I have, therefore, in the specification and claims used the term "flattening" 75 only to describe the operation or result of the process, and to avoid any conflicting use of the term "flattening" have referred to the first flattening of the body shown in Fig. 3 as a folding of the body in a line 80 through its apex. The first actual folding of the body which is shown in Fig. 4 is thus necessarily termed the folding of the body again, and where such term is used in the claims it will be understood to have the 85 meaning just described. The body of Fig. 4 is then ready for stretching, which may be effected by any suitable means, as the stretching-arms *e*, *e'* in Fig. 5, the arm *e* being forked to enter the two folds *c*, *c'*, 90 while the arm *e'* is inserted within the inner fold *d*. Such arms are shown extended within the entire length of the folds and mounted movably upon a segmental bed *f* upon which they are moved outwardly by a screw *k* 95 fitted to a bearing *k'* on the arms. The bed is shown provided with clamping-jaws *l*, *m*, arranged to grip the edge of the body intermediate to the arms *e*, *e'*, to prevent the body from sliding outwardly upon the arms as 100 their angle to one another is increased. The clamps are in practice separated automatically by a spring and pinched together by a clamp-screw *i* when the edges of the body are inserted between them. In the operation of such a stretching device, the arms *e*, *e'* operate upon the entire length of the folds, and stretch the intermediate parts of the body proportionately to their distance 105 from the apex.

The body is kept wet and hot during the stretching operation by any suitable means,

and is partially stretched and then released from the arms and from the clamp *m* and folded in a new position, such refolding and stretching being repeated to any desired extent, and operating gradually to expand the opening *b* of the body.

If a perfectly flat body, such as is shown in Fig. 2, is desired, the doubly folded body is stretched to the quadrantal form shown 10 in Fig. 6 which, when the folds are opened on the central line *j*—*j* of Fig. 2, produces a flat body, which may be used in any manufacture of hats to which it is adapted.

It is found in practice, that in order to 15 make a perfectly flat hat-body, it is very desirable to stiffen the body with the usual shellac solution before stretching the same, as the hardening of such stiffening when the stretching operation is completed helps very 20 materially to retain the hat-body in a flat form. If such a stretched body were pulled and dried without the stiffening, it would shrink and pucker and would not present the plane surface that is desired. I have, 25 therefore, made a special claim to the process which involves the stiffening prior to the stretching operation.

Having thus set forth the nature of the invention what is claimed herein is:

30 1. The process of stretching a conical hat-body, which consists in folding a hat-body on a line through the apex of the body, then folding such folded body again on a line through the said apex, forming four sectors of equal size, and then pulling the entire length of the folds apart to simultaneously stretch the portions intermediate to the folds.

2. The process of stretching a conical hat- 40 body into flat form, which consists in folding the body twice through its apex forming four thicknesses of fabric parallel to each other and operating upon the entire

length of the four folds to stretch the parts intermediate to the folds proportionately 45 to their distance from the apex, until the primary folds are in a line across the center of the body.

3. The process of stretching a conical hat-body, which consists in folding the body more than once through its apex, thereby 50 forming a plurality of folds, and then stretching the felt between the folds simultaneously and proportionately, from the apex of the cone to the base. 55

4. The process of stretching a conical hat-body, which consists first, in stiffening the body with the usual stiffening solution, then folding the body through its apex, forming two thicknesses of fabric, then folding again 60 through the apex to make four thicknesses of fabric parallel to each other, then stretching these four thicknesses simultaneously and proportionately, from the apex of the cone to the base. 65

5. The process of stretching a conical hat-body, which consists first, in stiffening the body with the usual stiffening solution, then folding the body through its apex, forming two thicknesses of fabric, then folding again 70 through the apex to make four thicknesses of fabric parallel to each other, stretching these four thicknesses simultaneously and proportionately, from the apex of the cone to the base, then changing the folds and repeating the folding and stretching until each of the thicknesses forms a quadrant of a circle, and the whole when opened forms a substantially flat disk. 75

In testimony whereof I have hereunto set 80 my hand in the presence of two subscribing witnesses.

FRANK J. MUHLFELD.
